UNITED STATES PATENT OFFICE.

DAVID F. STEIN, OF MONTREAL, CANADA.

BAG-TURNING MACHINE.

1,270,893.

Specification of Letters Patent.

Patented July 2, 1918.

Application filed July 8, 1916, Serial No. 108,112. Renewed December 24, 1917. Serial No. 208,702.

To all whom it may concern:

Be it known that I, DAVID F. STEIN, a subject of the King of Great Britain and Ireland, residing at Montreal, Canada, have 5 invented certain new and useful Improvements in Bag-Turning Machines, of which the following is a specification.

My invention relates to improvements in machines for turning bags, such as burlap 10 and jute bags or the like.

Bags of the character herein contemplated are manufactured in large quantities, and each consists of two like parts sewed together at three edges. The bags are sewed 15 on the wrong side, so that before they can be used they are required to be completely turned, and my machine is adapted to perform this work.

In United States Letters Patent No. 20 1,140,627 issued to me on May 25th, 1915, there is disclosed a machine for turning bags, and the present invention is a development of that shown in my said patent.

The principal object of the present invention is to provide a machine of greatly increased efficiency in regard to the output within a given period of time. I accomplish this object by an improved construction and operation of the bag holding and turning 30 mechanism.

Another object of the invention is to so construct the machine that its parts are adjustable to adapt it for operation upon different sized bags.

35 A still further object of the invention is to simplify and improve sundry parts and combinations of parts whereby the machine may be constructed at a relatively low cost and will be thoroughly accurate, rapid, and 40 generally satisfactory in operation.

Stated briefly in general terms, a machine constructed according to my invention embodies holding means by which the bags are suspended by their upper edges, together 45 with rotating members which are designed to engage the bag, free it from the holding members, and turn the bag in the course of their rotation. The bag holding members are preferably mounted to be capable of reciprocation so that as a bag is taken by the 50 turning members from a supporting member the latter moves into a position to have another bag placed thereon. In this way the machine can be worked continuously and its 55 output considerably increased over that of the machine disclosed in my earlier patent.

The preferred form of the invention is illustratively exemplified in the accompanying drawing, in which—

Figure 1 is a perspective view of my improved bag turning machine;

Fig. 2 is a vertical sectional view through the mechanism for adjusting the turning arms in relation to each other;

Fig. 3 is a similar view on the line 3—3 65 of Fig. 2;

Fig. 4 is a rear elevational view of the bag holding or supporting mechanism and appurtenant parts;

Fig. 5 is a front elevational view thereof 70 adapted particularly to disclose the reciprocating means for the bag holding mechanism;

Fig. 6 is a vertical sectional view on the line 6—6 of Fig. 4;

Fig. 7 is a side elevational view of a block carrying gripper jaws adapted to engage the upper edges or mouths of the bags;

Fig. 8 is a fragmentary sectional view of one of the turning arms showing a cam 80 therein for closing the gripper jaws of Fig. 7; and

Fig. 9 is a similar view showing a cam for opening said jaws.

The machine illustrated in its present embodiment comprises a preferably horizontal frame which is designated generally as 10 and supports the entire operative mechanism. At one end of the frame 10 is arranged gearing and driving mechanism 90 which is designated generally as 11 and will not be specifically described except as may be necessary for the explanation of the operation of special parts of the machine. At its opposite end the frame 10 carries a train 95 of gears 12 adapted to rotate a roller 13 over which an endless apron 14 passes, on to which apron the bags fall, after having been turned, as will be more fully herein-after explained. 15 denotes a presser roller 100 resting upon the apron 14 and designed to press the bags as they are carried upwardly on the upper reach of the apron 14. The lowermost wheel of the gear train 12 is driven by any suitable means, not shown in the 105 drawings.

Projecting from the base of the frame 10 is a supporting pillar 16 provided with a bearing 17 at its upper end. This bearing is designed to receive the rotary supporting 110 member for the turning arms. Within the bearing 17 is mounted rotatably a sleeve 18

which has secured thereto by means of screws 19 or the like a sleeve or ring 20, having formed integrally therewith a bevel gear wheel 21. The ends of the ring 20 are 5 adapted to rotate between and be guided by the blocks or lugs 17^a forming part of the bearing 17.

The sleeve 18 is substantially cylindrical and incloses a pair of similar blocks 22 each 10 of which has a central threaded opening to receive a screw spindle 23, which is threaded in opposite directions at each side of its median line or center. In addition to supporting the screw spindle 23, the blocks 22 15 have the function of tightly holding within the sleeve 18 a plurality of rods 24. In the drawing, four such rods are shown, projecting in pairs in opposite directions beyond the ends of the sleeve 18. Those ends of the 20 rods 24 which are within the sleeve 18 are held in position by means of screws 25 entering the rods axially and abutting the adjacent ends of the blocks 22. As will be noted particularly from Figs. 2 and 3, the blocks 25 22 are provided with semi-cylindrical grooves, and the inner face of the sleeve 18 is provided with complementary semi-cylindrical grooves, each pair of grooves in the block and sleeve respectively, being adapted 30 to form a seat to receive one of the rods 24. There is a driving fit between the rods 24 and blocks 22, whereby the rods will move with the blocks in the sleeve 18.

At their projecting ends the rods 24 engage blocks 26, such rods being firmly held in the blocks by means of the countersunk screws 27. Additional means for preventing the rods 24 from working loose in the blocks 26 are provided in the form of cap plates 28 40 secured by screws 29 against the outer faces of the blocks 26.

Each block 26 is centrally apertured, such apertures being designed to receive the ends of the spindle 23. The opposite ends of the 45 spindle 23 are squared as at 23^a for the purpose of receiving a suitably shaped socket of an operating crank 30. The cap plates 28 are orificed to permit the crank to engage the squared ends of the screw threaded 50 spindle.

Projecting radially from each block 26 is a plurality of bag turning arms 31. Any desired number of arms may be employed. In the drawing each block 26 is shown as 55 carrying three such arms, the arms in the opposite blocks being alined so as to form parallel pairs of bag turning members. The arms 31 are preferably set in sleeves or sockets 32 which are suitably secured in the blocks 26, as is more especially illustrated in Fig. 2.

Rotation is imparted to the blocks 26 through the intermediary of a beveled gear 33, which meshes with the gear 21 formed as 60 an integral part of the sleeve 20. The gear

33 is carried at one end of a vertically inclined shaft 34, the opposite end of which (Fig. 5) carries a bevel gear wheel 35 in mesh with a bevel gear wheel 36 fast on a stub shaft 37 driven from the power 70 source 11.

Each arm 31 is hollow, having a ball or knob 38 at its free end, such arm being also preferably somewhat curved at its free end. As will be noted from Fig. 1, each arm 31 75 is provided with a lateral slot 39 extending substantially the entire length of the arm.

Slidable in each arm 31 is a gripping member (Fig. 7) which comprises a substantially cylindrical block 40 carrying a pair of gripper jaws. The lower jaw 41 is stationary and preferably formed integral with the block 40, while the upper jaw 42 is pivotally mounted at 43, and has a rearwardly extending tail or arm 44 capable of projecting 85 through an elongated slot (not shown) in the body of block 40. The jaws are normally held apart by a coiled spring 45 interposed therebetween.

Mounted on a pin 46, in the block 40, is a 90 flat spring 47, which, under conditions to be explained, is adapted to move under the extended arm 44 of the jaw 42, and hold the latter in gripping engagement with the jaw 41.

Each block 40 is pivotally connected by means of a stud 48 near its rear end with one end of a rod 49, the other end of which is loosely pivoted about a stub shaft 50 held in a bracket 51 projecting upwardly from 100 the frame 10. This stub shaft also carries or supports an arm 52 the inner end of which is provided with a collar 53 (Fig. 2) which fits into a rectangular groove formed at the outer face of the block 26 and steadies the 105 latter during its rotation. Within each arm 31, near its outer end is a cam 54 which is so shaped as to be capable of engaging the under face of the extended arm 44 of the jaw 42 and forcing the latter downwardly 110 into engagement with the jaw 41. When the two gripper jaws are in engagement, having been placed in this position by co-operation of the extension 44 with the cam 54, the flat spring 47 passes under the extension 44 and 115 maintains the gripper jaws in engagement.

Near the inner end of each arm 31 is a second cam 55 which is longer and lower than the cam 54, and the function of which is to press the flat spring 47 aside so as to permit 120 the coiled spring 45 to extend and separate the gripper jaws. In Fig. 7 the opened position of the jaws is indicated in full lines and the engaging position in dotted lines.

The bag supporting mechanism is arranged at the forward end of the machine in such position as to present the mouths of the bags to the turning arms as the latter rotate. The preferred arrangement of parts of the bag supporting mechanism will now be de- 125 130

scribed. Resting upon the forward end of the upper portion of the machine frame 10, or formed integrally therewith if desired, is a trough shaped guide 56 in which is adapted to reciprocate a carriage 57, the latter moving back and forth on rollers 58 to minimize friction. The rear end of the guide 56 is open, and projecting through the opening therein is a portion of the carriage 57 into which is dove tailed the lower end 59 of the bag supporting uprights. The lower end of each bag supporting upright comprises spaced bent arms 60 adjacent one of each of which is a spring tongue 61 to temporarily hold the bag in position on the supporting member.

Each of the uprights 59 is provided near its lower end with a transverse threaded opening through which extends a screw 20 spindle 62 the opposite ends of which are squared as at 63 to receive a suitable tool by means of which the spindle may be rotated. As will be noted from Fig. 4 the spindle is preferably formed of sections held together, 25 end to end, by a plurality of sleeves 64.

The front of the guide 56 is slotted at 65 and projecting through the slot is a stud 66 secured to the carriage 57. Pivotedly connected with the stud 66 is one end of a link 30 67, the other end of said link being pivotally connected to an arm 68 which pivots at 69 on a bracket 70 forming part of the machine frame. Intermediate its ends the arm 68 is pivotally connected at 71 to one end of a bar 35 72 the opposite end of which is pivotally connected at 73 to a relatively short arm 74, rigidly mounted on a shaft 75. On said shaft 75 is a beveled gear 76 in mesh with a similar gear 77 secured to the stub shaft 37. 40 The retracted and advanced positions, respectively, of the carriage 57 with its bag supporting arms are indicated by dotted and full lines in Fig. 5.

Projecting upwardly from the base of the frame 10 and extending substantially parallel to the pillar 16 is a rod 78, the function of which is to strip a bag from the arms 31 if such bag does not fall by gravity on to the apron 14.

50 It will be understood that bags are of different standard widths, and my machine is adapted for turning bags of different widths ranging from the minimum to the maximum. In the course of operation, as will be presently described, each of the turning arms 31 moves between a pair of adjacent arms 60 of the bag supporting members, and it is therefore necessary to adjust the distance between the pairs of bag supporting members 55 and the pairs of arms 31 in correspondence. To adjust the space between the pairs of arms 31 it is merely necessary to rotate the screw spindle 23 in the desired direction whereby the arms 31 will be drawn either 60 closer together or moved farther apart. The spindle 23 having a right hand and a left hand thread it will be understood that the arms 31 on opposite sides of the center of the spindle 23 will be moved like distances in opposite directions by actuation of said 70 screw spindle.

To adjust the space between the supporting members 59, 60, it is simply necessary to rotate the spindle 62 to the desired extent and in the desired direction by means of the 75 crank 30.

Assuming that the adjustments have been made as above suggested, the operation of the device is as follows:—The bags, inside out, are hung with their upper edges overlapping the upper ends of two pairs of the spaced arms 60, the body of the bag depending from these arms. The spring tongue 61 prevents the bag from falling off the arms. The turning arms 31 are caused to revolve 85 through the intermeshing gearing 21 and 33 and the mechanism which rotates this gearing. The carriage 57 is reciprocated in the guide 56 through the beveled gears 76 and 77 and the link mechanism shown in Fig. 5. 90 There are suitable dwells in the reciprocatory movement of the carriage 57 to permit the arms 31 to take the bags from the arms 60. These dwells occur during the period that the short arm 74 moves idly downward 95 in the arc of a circle from substantially the position shown in Fig. 5 to the corresponding position below the shaft 37, and during the period that the arm 74 moves idly upward at the left hand side of the shaft 75. 100

As the arms 31 rise the rods 49 will cause the block 40 and the gripping mechanism which it supports to be moved toward the forward ends of the arms 31. The gripping jaws 41 and 42 project outwardly 105 through the lateral slots 39 in the arms 31.

As the arms 31 pass up between adjacent arms 60 the gripping jaws 41, 42 will engage the overlapped ends of the bags held on the arms 60 and as the arms 31 are slightly past 110 the horizontal the cam 54 will close the jaws 41, 42 and grip the bag, and in the continued rotary travel of the arms 31 the bag will be drawn down over its arms by the gripper jaws.

It being borne in mind that the block 115 40 is pivotally connected to the rod and that the latter is considerably shorter than the arm 31, the arc of the circle described by the outer end of each rod 49 will be considerably smaller than that described by the outer end 120 of each rod 31, so that it is apparent that as both the arms 31 and bars 49 rotate the bag will be completely turned. Each adjacent pair of supporting members 59, 60 supports a single bag and each parallel pair 125 of arms 31 is designed to turn a single bag. As a pair of arms 31 supporting a bag reaches about a horizontal position opposite the supporting members 59, 60 the spring 47 will be engaged by the cam 55 130

and turned aside thus permitting the spring 45 to extend and separate the jaws 41 and 42, and on the further rotation of such pair of arms, and when the latter are directed at 5 a downwardly inclined angle, the bag will fall from the arms 31 by gravity on to the traveling apron 14 and be carried to any desired place. If for any reason the bag should not fall by gravity from the arms 31 10 it will strike the rod 78 and be stripped from the arms. In practice, the rod 78 is inclined at such an angle from the vertical, that any bags still held by the arms 31 as the latter approach the vertical position, 15 are stripped from such arms so that the latter are free as they travel upward.

The machine may be worked at relatively high speed and while in the drawing I have shown 3 pairs of turning arms upon a single 20 center, and a number of supporting arms appropriate to the turning arms, it will be readily apparent that the turning arms may be multiplied in pairs as desired and the supporting members correspondingly multiplied. The machine illustrated in the drawing 25 may be served by a single operator, who can with ease place bags on the supporting members 59, 60 as rapidly as these can be taken and turned by the rotating arm 31.

30 What I claim is:—

1. In a machine of the character described, the combination of bag supporting mechanism reciprocable in a rectilinear path transversely of the machine and bag turning 35 mechanism rotatable in a plane substantially at right angles to the path of reciprocation of the bag supporting mechanism.

2. In a machine of the character described, the combination of bag supporting 40 mechanism comprising spaced arms, means for reciprocating said arms in a rectilinear path, rotary arms adapted to receive bags from said supporting mechanism, means car-

ried by and coöperable with said rotary arms to engage bags and turn the same, and 45 means for rotating the rotary arms in a plane substantially at right angles to the path of reciprocation of the bag supporting mechanism.

3. In a machine of the character described, the combination of a carriage, bag supporting arms therein, means for reciprocating said carriage in a rectilinear path, rotary arms for receiving bags from said first named arms, means carried by and coöperable with said rotary arms for turning bags, and means for rotating said rotary arms in a plane substantially at right angles to the path of reciprocation of the carriage. 50

4. In a machine of the character described, the combination of reciprocating bag supporting mechanism comprising spaced arms, means for adjusting the distance between said arms, means for reciprocating said bag supporting mechanism in a 55 rectilinear path, bag turning mechanism comprising rotary arms and means for adjusting the distance between said rotary arms, and means for rotating said bag turning mechanism in a plane substantially at 70 right angles to the path of reciprocation of said bag supporting mechanism.

5. In a machine of the character described, the combination of bag supporting mechanism, means for reciprocating the 75 same in a rectilinear path, bag turning mechanism, and means for rotating the same in a plane at right angles to the path of reciprocation of said bag supporting mechanism.

In witness whereof I have hereunto set my hand in the presence of two witnesses.

DAVID F. STEIN.
